UNITED STATES PATENT OFFICE

2,667,816

OPERATING SLIDE AND BOLT FOR FIREARMS

Clarence E. Simpson, Wilbraham, Mass., assignor to the United States of America as represented by the Secretary of War

Original application October 29, 1948, Serial No. 57,283. Divided and this application March 16, 1950, Serial No. 150,065

1 Claim. (Cl. 89—149)

(Granted under Title 35, U. S. Code (1952), sec. 266)

1

The invention described herein may be manufactured and used by or for the Government without the payment of any royalty thereon.

This invention relates to gas operated automatic firearms and is particularly directed to a simplified construction wherein a reciprocable operating slide is coupled to a reciprocable bolt only during the interval in which the breech is unlocked and the bolt is free to recoil and counter-recoil.

This application is a division of my copending application Serial No. 57,283, filed October 29, 1948, and now matured into U. S. Patent No. 2,576,973.

In those automatic firearms in which a firing pin is slidably carried within a reciprocating bolt, it is of extreme importance that actuation of the firing pin be delayed until the bolt is securely locked in a battery position. It is also important that unlocking of the bolt be delayed until the relatively high gas pressures generated by the discharge of a cartridge have dropped sufficiently low to permit safe extraction of the empty cartridge case. Therefore, if an operating slide is used to actuate the bolt, it is necessary that such slide be disassociated from the bolt for certain intervals of time in order that the above-mentioned delays can be effected. This has been adequately accomplished in the art but has necessitated either the use of rather complicated linkage mechanism for connecting the operating slide to the bolt or has required a camming movement of the bolt away from direct longitudinal reciprocation.

Consequently, it is an object of this invention to provide a simple yet reliable latching means for coupling an operating slide to a bolt.

It is a particular object of this invention to provide a bolt and operating slide mechanism wherein the slide will travel independently of the bolt during such time as the latter remains in a locked battery position.

The specific nature of the invention as well as other objects and advantages thereof will clearly appear from a description of a preferred embodiment as shown in the accompanying drawings in which:

Fig. 1 is a longitudinal cross-sectional view of a firearm embodying the structure of the present invention, the recoiling parts being shown in battery position;

Fig. 2 is a view similar to Fig. 1 but showing the recoiling parts in a fully recoiled position;

Fig. 3 is a cross-sectional view of the bolt;

Fig. 4 is a top view of the operating slide;

2

Fig. 5 is a longitudinal sectional view of the operating slide; and

Fig. 6 is a rear end view of the firearm receiver.

5 Referring to the drawings there is illustrated a portion of a firearm embodying the construction of the present invention. The firearm essentially comprises a receiver 5 to the front end of which a barrel 6 is fixedly secured as by threads 7, a bolt 8 arranged to reciprocate along suitable longitudinal ways 9 provided within the interior of receiver 5, and an operating slide 10 mounted beneath bolt 8 and also arranged to reciprocate longitudinally along suitable ways 11 within receiver 5.

Bolt 8 is formed with a substantially cylindrical body portion 12 which terminates in a depending rectangular base portion 13 arranged to slidably engage in ways 9. A firing pin 14 is slidably carried in an axial hole 15 provided through body portion 12 of bolt 8. The rear end of hole 15 is enlarged as shown best at 16 in Fig. 3 and communicates with a substantially rectangular opening 17 extending upwardly from the bottom 20 of bolt 8 and having a front and rear wall surface indicated by 25 and 24, respectively. The junction of the enlarged rear end portion 16 of firing pin hole 15 and rectangular opening 17 provides access for a tang portion 18 integrally formed at the rear end of firing pin 14. A substantially semi-annular groove 19 is provided at the forward end of cylindrical body portion 12 of bolt 8 and is arranged to seat a mating bolt lock 20 which is slidably mounted for vertical movement in a suitable guideway 21 formed in receiver 5.

Operating slide 10 is a substantially rectangular member having a longitudinally extending slot 22 through which bolt lock 20 is arranged to extend. A vertically disposed lug 23 projects upwardly from the rear end of slide 10 and is arranged to extend into rectangular opening 17 of bolt 8 and contact wall surfaces 24 and 25 in a manner to be hereinafter explained. A transverse slot 26 in operating slide lug 23 is arranged to receive tang 18 of firing pin 14. Thus operating slide 10 serves as a hammer and actuates firing pin 14 to discharge a cartridge 27. Suitable cam grooves 28 and 29 are formed in the top and bottom surfaces of operating slide 10 and are arranged to actuate bolt lock 20 in a manner fully described in the aforementioned U. S. Patent No. 2,576,973.

In the battery position of bolt 8 and slide 10, a front end portion 30 of the latter projects forwardly beyond the end of receiver 5 into a rectangular housing 31 suitably secured beneath

barrel 6 and parallel thereto. Front end portion 30 of slide 10 is provided with a threaded longitudinal hole 32 arranged to receive the rear end of a hollow operating piston 33. An operating spring 34 and guide rod 35 are associated with piston 33 in a manner fully disclosed in Patent No. 2,476,328, dated July 19, 1949.

The rear end of longitudinal slot 22 in operating slide 10 is extended to form a narrower slot portion 36 arranged to receive a latch 37 which is pivotally secured to slide 10 as by a transverse pin 38. Latch 37 is a substantially L-shaped member having a short and a long leg portion 39 and 40, respectively, and is arranged to be disposed within slot portion 36 so that short leg portion 39 contacts the rear wall of slot portion 36, such wall being rearwardly inclined as shown at 41 in Fig. 5. An angularly disposed cylindrical recess 42 extends into slide 10 beneath lug 23 and is arranged to seat a spring 43 and a slidable plunger 44 which contacts leg portion 39 of latch 37 and provides bias thereto in a counterclockwise direction. A latching shoulder 45 is provided on leg portion 40 and is arranged to mate with an oppositely formed shoulder 46 on the bottom of bolt 8. The forward end of leg portion 40 of latch 37 is beveled as shown at 47 to permit positive entry thereof into a rectangular opening 48 extending through bolt lock 20. The upper wall of bolt lock opening 48 is provided with a cam surface 49 arranged to be contacted by the front end of leg portion 40 of latch 37.

In the battery position illustrated in Fig. 1, operating slide 10 is fully forward in contact with the front wall 25 formed in bolt 8 by rectangular opening 17. Leg portion 40 of latch 37 projects forwardly through rectangular opening 48 in bolt lock 20. When cartridge 27 is discharged by firing pin 14, the generated gases act upon the front end (not shown) of operating piston 33 and provide recoil movement thereto. Since bolt lock 20 is engaged with groove 19 in bolt 8, only the operating slide 10 moves rearwardly and retracts firing pin 14. As slide 10 recoils, bolt lock 20 is cammed upwardly to disengage from bolt 8 whereupon the latter is free to recoil as soon as vertical lug 23 on slide 10 contacts the rear wall 24 in bolt 8. During this so-called "dwell period," latch 37 has been withdrawn from rectangular opening 48 in bolt lock 20 and has been rotated by spring-biased plunger 44 so that latch shoulder 45 is engaged with shoulder 46 on bolt 8. Operating slide 10 and bolt 8 recoil simultaneously and contact a suitable buffer plate 50 provided at the rear end of receiver 5. Since operating spring 34 has been compressed during recoil, sufficient energy has been stored to provide for counter-recoil movement.

Bolt 8 and operating slide 10 continue to move together during counter-recoil due to the engagement of latch 37. Cartridge 27 has been positioned by suitable feeding mechanism (not shown) in front of bolt 8 so that such cartridge can be chambered as bolt 8 continues forwardly.

Simultaneously with the completion of such chambering, the front end of latch leg 40 contacts cam surface 49 on bolt lock 20 and is thereby disengaged from bolt shoulder 46. As a result, slide 10 moves forwardly to actuate bolt lock 20 into engagement with semi-annular groove 19. Operating slide 10 then continues to move forwardly and actuate firing pin 14 to fire cartridge 27 whereupon the firing cycle is repeated.

It will thus be readily apparent to those skilled in the art that there is here provided a simple yet positive connection between an operating slide and bolt which will permit movement of the two members as a unit and yet assure disengagement therebetween at exactly the proper times to permit a dwell period during unlocking of the bolt upon recoil and a safe period during counter-recoil so that the bolt can be positively locked prior to actuation of the firing pin.

I claim:

In a firearm having a receiver, a bolt slidably mounted in the receiver for reciprocating movement between a battery position and a recoiled position, a reciprocable operating slide slidably mounted in said receiver beneath said bolt, vertical lug means adjacent the rear end of said operating slide, a firing pin slidably carried in said bolt and having a depending tang portion at the rear end thereof, said bolt having an opening extending upwardly from the bottom thereof arranged to receive said lug means in engagement with said firing pin tang portion, said opening in said bolt being of greater length than said lug means whereby said operating slide is free to reciprocate relative to said bolt, a shoulder in the bottom of said bolt disposed forwardly of said opening therein, latch means pivotally secured to said operating slide, resilient means for biasing said latch into engagement with said shoulder at the conclusion of the rearward movement of said slide relative to said bolt whereby said bolt and said slide reciprocate together, and means for disengaging said latch from said bolt when the latter has reached battery position whereupon said slide is free to move forwardly and actuate said firing pin.

CLARENCE E. SIMPSON.
